LIQUEFACTION OF GASES.

1,027,817.

Specification of Letters Patent.

Patented May 28, 1912.

Application filed December 28, 1906. Serial No. 349,922.

To all whom it may concern:

Be it known that I, GEORGES CLAUDE, administrateur de la Société "L'Air Liquide" (Sté. Anonyme pour l'Étude et l'Exploitation des Procédés Georges Claude,) a citizen of the Republic of France, and resident of 43 Rue St. Lazare, Paris, France, have invented Improvements in the Liquefaction of Gases, of which the following is a

10 description.

This invention relates to the liquefaction of atmospheric and other gases and has particular reference to the process described in the specification of an application for Letters Patent of the United States, Serial No. 139,753, filed Jan. 2, 1903 in which, from the point of view of the frigorific efficiency, the importance has been set forth of raising as much as possible the temperature at which 15 the expansion with external work of the compressed air takes place in liquid air machines. With this object, instead of liquefying a portion of the air which is expanded, the course has been adopted of utilizing its 20 cooling effect for causing the liquefaction of a distinct portion of compressed and cold air; this latter, by reason of its pressure, liquefies at a much higher temperature than could the expanded air itself, and, consequently, causes a general rise in the working 25 temperatures. In the same connection, it has been proposed to effect the expansion of the compressed air in several stages, each partial expansion being followed, as indicated above, by the liquefaction (owing to the low temperature of the partially expanded air) of a distinct portion of compressed air; the partially expanded air thus 30 becomes re-heated and capable of accomplishing its following partial expansion under more favorable conditions.

According to the present invention the two methods above indicated are utilized with new conditions which constitute a considerable improvement in the same direction. This improvement is obtained by supplying the liquefier or liquefiers employed in the process with previously cooled compressed oxygen, its pressure being preferably adjacent to the critical pressure, say fifty (50) atmospheres.

As the critical temperature of oxygen is -118° C. as compared with -140° C. for air, all other conditions being equal, the

working temperatures may be established 55 at about 20° C. above those which would exist when air is used in the liquefier and this difference in temperature is very large at these temperatures which are comparatively close to the absolute zero, particularly if the imperfection of the gaseous state of compressed air at these temperatures be taken into account. It will therefore be seen that the employment of compressed oxygen constitutes a great improvement 60 in regard to the working temperatures. Obviously it is liquid oxygen and not liquid air which will be obtained under these conditions.

In cases in which the liquid obtained is 70 intended to serve as a reserve or supplementary supply for apparatus for extracting oxygen from air instead of the liquid air generally used for this purpose, the process may be applied in the following manner: 75 At the beginning of the operation, that is to say before the oxygen apparatus has been started the liquefier or liquefiers may be supplied with a part of the supply circuit of the apparatus, or with compressed air 80 drawn from another source in conformity with the process set forth in the specification of the aforesaid application Serial No. 139,753. It is also possible to employ compressed oxygen, arising from a preceding 85 operation for example. As soon as the apparatus is started, and oxygen gas liberated, a portion of said gas, after its coldness has been utilized, is compressed by means of an auxiliary compressor which may for example be actuated by power derived from the work due to expansion; the compressed gas is then sent into the liquefier or liquefiers, after having been cooled by its passage 90 through temperature exchangers which are 95 traversed in the opposite direction either by a portion of the expanded air of the apparatus, or by a portion of the vaporized gases of the separator apparatus. A convenient method is to utilize a special exchanger 100 traversed on the one hand by the oxygen sucked by the compressor and on the other hand by the compressed oxygen produced; in this manner, the regulation is automatic. In proportion as it is produced, the liquid 105 oxygen is decanted into the vaporizer vessel of the separator apparatus; it is not necessary to take into account the oxygen in-

tended for the liquefier in the regulation of the separator apparatus, because the gaseous oxygen which proceeds toward the compressor and the liquefier returns therefrom in the form of liquid.

For similar reasons to those set forth with respect to the employment of oxygen, it might be advantageous to operate in the expansion apparatus with nitrogen resulting from the separation of the air, this gas being more difficult to condense than air, and, consequently, being capable of expanding under better conditions.

The accompanying drawing represents by way of example an arrangement of apparatus for carrying the invention into practice.

This arrangement consists broadly of the exchanger A, where the compressed air and the expanded air circulate in opposite directions, of the exchanger L to which compressed oxygen is supplied and in which the expanded air circulates likewise in the reverse direction, of the liquefier E C and of the expansion machine B D. The compressed oxygen enters the exchanger L at 8, traverses the nest of tubes of the exchanger; which it leaves cooled through the pipe 9, the latter conducting it into the nest of tubes of the liquefier E C through which it passes in the downward direction, and where it becomes liquefied. The liquid oxygen may be drawn out of the apparatus through the cock G, or conducted through the cock H and the pipe J to the separator apparatus, where it serves as reserve or supplementary liquid. On the other hand, the compressed air enters the exchanger A at I, passes through the nest of tubes in this exchanger, which it leaves cooled through the pipe 2 the latter conducting it to the first expansion cylinder B of the expansion machine B D where it is subject to a partial expansion. The cooled expanded air is conducted through the pipe 3 into the upper part C of the liquefier E C, which it traverses in the upward direction in liquefying the compressed and cold oxygen contained in the nest of tubes; reheated owing to this liquefaction the air then proceeds through the pipe 4 to the second cylinder D of the machine, there it is expanded completely and consequently cooled, from there the pipe 5 conducts it into the lower part E of the liquefier E C, after having caused in E the liquefaction of the compressed oxygen in the nest of tubes, the expanded air leaves the liquefier by the pipe 6; the cock K enables a portion of it to be conducted through the pipe 6^x into the oxygen exchanger L, where it cools the compressed oxygen before its admission to the liquefier, the air escaping finally into the atmosphere through the pipe 10; the other portion of the expanded air, which is the most important portion, passes

through the pipe 6 into the principal exchanger A where it cools the compressed air to be expanded, and finally escapes into the atmosphere through the pipe 7.

If it is desired to employ nitrogen as expansion gas, it will traverse the circuit 1, A, 2, B, 3, C, 4, D, 5, E, 6, A, 7, previously indicated for the compressed air.

The reasons for employing oxygen for improving the conditions of liquefaction likewise hold good for its employment in expansion without external work. It is indeed known that this method of expansion is exclusively based upon the performance of internal work due to the fact that at the initial temperature of the cycle the gas in question is not a perfect gas. Now in the case of oxygen all other things being equal, this imperfection is far more accentuated than in the case of air, so that the efficiency of the liquefying apparatus will be largely increased if it be supplied with oxygen.

It is obvious that this method which consists in supplying the liquefier or liquefiers with a compressed gas which is different from that which is expanded, and presenting relatively to the latter a higher critical temperature, might present the same advantages in other analogous cases, for example, in the case of water gas.

Claims:

1. The method of liquefying permanent gases which consists in subjecting a compressed and cooled permanent gas to the indirect cooling action of another expanded permanent gas with a lower critical temperature, the remaining cold of which after being utilized for liquefying purpose is used in cooling both compressed permanent gases the one to be liquefied and the other to be expanded.

2. The method of liquefying permanent gases which consists in compressing and cooling the permanent gas to be liquefied and a refrigerating permanent gas whose critical temperature is lower than that of the gas to be liquefied, subjecting the compressed gas with the higher critical temperature to the indirect cooling action of the gas with the lower critical temperature which is itself cooled by successive expansions, the cooling action taking place after each expansion and the remaining cold of which after being utilized for liquefying purpose is used in cooling both compressed permanent gases the one to be liquefied and the other to be expanded.

3. The method of liquefying oxygen gas which consists in subjecting compressed and cooled oxygen gas to the indirect cooling action of expanded gaseous air, the remaining cold of which after being utilized for liquefying the oxygen is used for cooling the compressed oxygen and the compressed air.

4. The method of liquefying oxygen gas

which consists in compressing and cooling apart oxygen gas and air, subjecting the compressed oxygen to the indirect action of the gaseous air which is itself cooled by successive expansions, the cooling action taking place after each expansion and using the remaining cold of the expanded air to cool the compressed oxygen and the compressed air.

5. The method of liquefying oxygen gas which consists in compressing and cooling apart oxygen gas and air, allowing the air to partially expand with production of external work, transmitting the cold of this partially expanded air to the cooled com-

pressed oxygen, further expanding the air 15 with production of external work and subjecting the cooled compressed oxygen to the cooling action of this finally expanded air and further utilizing the remaining cold of this expanded air to cool both the compressed oxygen gas and the compressed air, substantially as set forth.

20 In testimony whereof I affix my signature in presence of two witnesses.
